US00D958761S

(12) **United States Design Patent** (10) **Patent No.:** **US D958,761 S**
(45) **Date of Patent:** **** Jul. 26, 2022**

(54) **CONTROL DEVICE**

- (71) Applicant: **Lutron Technology Company LLC**,
Coopersburg, PA (US)
- (72) Inventors: **Gregory Altonen**, Easton, PA (US);
Chris Dimberg, Easton, PA (US);
Jason C. Killo, Emmaus, PA (US);
Matthew Philip McDonald,
Phoenixville, PA (US); **Gregory M.**
Snyder, Germansville, PA (US); **Daniel**
L. Twaddell, Allentown, PA (US)
- (73) Assignee: **Lutron Technology Company LLC**,
Coopersburg, PA (US)

(**) Term: **15 Years**

(21) Appl. No.: **29/740,579**

(22) Filed: **Jul. 6, 2020**

(51) LOC (13) Cl. **13-03**

(52) U.S. Cl.

(57) **CLAIM**

The ornamental design for a control device, as shown and described.

DESCRIPTION

FIG. 1 is a front perspective view of control device showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a front perspective view of a second embodiment thereof;

FIG. 8 is a front view thereof;

FIG. 9 is a left side view thereof;

FIG. 10 is a right side view thereof;

FIG. 11 is a top view thereof; and,

FIG. 12 is a bottom view thereof.

The dashed broken lines illustrate structure or features which form no part of the claimed design.

1 Claim, 8 Drawing Sheets
